US00D771953S

(12) **United States Design Patent** (10) **Patent No.:** **US D771,953 S**
Jimenez et al. (45) **Date of Patent:** **** Nov. 22, 2016**

(54) **HEAD PORTION OF AN ORAL CARE IMPLEMENT**

(71) Applicant: **COLGATE-PALMOLIVE COMPANY**, New York, NY (US)

(72) Inventors: **Eduardo Jimenez**, Manalapan, NJ (US); **John Gatzemeyer**, Hillsborough, NJ (US); **Robert Moskovich**, East Brunswick, NJ (US); **Alan Sorrentino**, Cranbury, NJ (US); **Alberto Mantilla**, Millburn, NJ (US); **Jason Liang**, Fresh Meadows, NY (US); **Lucas Wade**, Brooklyn, NY (US)

(73) Assignee: **COLGATE-PALMOLIVE COMPANY**, New York, NY (US)

(**) Term: **14 Years**

(21) Appl. No.: **29/500,314**

(22) Filed: **Aug. 25, 2014**
